RALPH A. GAERTNER, OF SAN PEDRO, CALIFORNIA.

ADJUSTABLE FIRING CHAMBER FOR SOLID-INJECTION ENGINES.

1,413,466.

Specification of Letters Patent. Patented Apr. 18, 1922.

Application filed June 2, 1920. Serial No. 335,956.

To all whom it may concern:

Be it known that I, RALPH A. GAERTNER, a citizen of the United States, residing at San Pedro, in the county of Los Angeles and 5 State of California, have invented new and useful Improvements in Adjustable Firing Chambers for Solid-Injection Engines, of which the following is a specification.

This invention relates to prime motors of 10 the Diesel type.

It is an object of the invention to provide an engine of this type in which the volume of the firing chamber may be readily adjusted.

15 The invention will be readily understood from the following description of the accompanying drawings, in which—

Figure 1 is a sectional view of the upper portion of the piston cylinder of an engine 20 showing in detail the construction of the firing chamber.

Fig. 2 is a transverse section on the line 2—2 of Fig. 1.

The engine of the present invention is of 25 the type in which a low gravity fuel oil is supplied in intermittent charges through the feed pipe 2, entering a block 3 having a valve seat 4 surrounding the passage way 5 which is closed by the outward movement of 30 a valve member 6 in the form of a ball supported on the expansile spring 7, the lower end of which bears, for instance, on the upper end of a nozzle 8 that is removably mounted in a bushing 9, longitudinally and 35 centrally bored at 10 to receive the nozzle 8 which projects downwardly into a chamber 11 formed in a removable block 12 fitted into a bore 13 in the head 14 of the engine casing or cylinder 15. Within this cylinder is op- 40 erative the usual piston 18, which, on the downward stroke may operate to open an air inlet valve 19 and on the return stroke compresses the air under the head of the cylinder.

45 In the embodiment of the invention illus- trated, means are provided for the retention of the successive charges of fuel introduced into the chamber 11 from the nozzle 8 so that gases therefrom will be readily ignited 50 when the pressure in the cylinder reaches a predetermined degree combined with the temperature of the block 12, and this ignition of a charge in the chamber 11 will result in the expulsion of the non-ignited vapors 55 from the chamber 11 in an atomized condition into the power chamber in which the piston

operates. This retention of fuel is secured by providing at the bottom of the chamber 11 a basin 21 in the form of a shallow recess formed below the contracted passage way 22 60 at the lower end of the chamber 11 and which passage way discharges into the enlarged pocket 23, Fig. 2, the bottom of which forms a basin 21, the front portion of the basin being formed by a lip or wall 24 shown 65 as provided with apertures 25, radially disposed and having their outer ends flared or enlarged as at 26 to facilitate the issue and expansion of the liquids, vapors, and gases, as they are forced out of the pocket 23 by 70 the pre-ignition of the vapors of the oil in the basin 21.

The upper body portion of the block 12 is made of predetermined and calculated thickness so as to retain a suitable degree of heat 75 to co-operate with the heat of compression of the air charged in the expulsion or piston chamber when a portion of this compressed fluid or air in the chamber 11 reaches an igniting point. This initial ignition causes 80 the expansion of the vapors and gases and their discharge from the chamber 11 carrying with them the liquid from the basin 21, the whole passing rapidly and in a thoroughly carbureted condition through the ap- 85 pertures 25 into the piston chamber where the maximum expansion effect of the igniting vapors operate in the usual manner impulsively on the piston.

It will be understood that a usual water 90 jacket 30 is provided in block 12 so as to surround the chamber 11 in usual manner in order to provide for the obtaining of the proper temperature of block 12 in order to cause the engine to function in the manner 95 set forth while employing a low gravity fuel oil.

The improved engine contemplates the em- ployment of means for readily and accurately adjusting the size of chamber 11 so 100 that the required compression may be ob- tained for various grades of fuel and at va- rious altitudes and under varying climatic conditions.

For this purpose bushing 9 is shown as 105 threaded into block 12 as by the threaded connection 20 so that the end of said bushing may be adjusted longitudinally within cham- ber 11 for increasing or decreasing the volume of said chamber. Bushing 9 may be 110 thus threaded into block 12 by a suitable wrench engaging a head 21 provided upon

said bushing. A lock nut 22' is, preferably arranged to retain the bushing in adjusted positions.

- Thus it will be seen that I have provided
5 a construction whereby the required compression within the firing chamber of an internal combustion engine of the Diesel type may be positively and easily obtained by adjusting bushing 9 so that the necessary compression may be obtained for causing the
10 most efficient operation of the engine, regardless of lost compression due to leaking valves and the like and also irrespective of the particular grade of fuel employed.
15 Various changes may be made without departing from the spirit of the invention as claimed.

What is claimed is:

1. In a solid injection internal combustion engine, a firing chamber comprising a fuel receiving portion, and a basin below the same communicating with the fuel receiving portion, said firing chamber having means for varying the volume of the same. 20

2. In a solid injection internal combustion engine, a firing chamber communicating with a working cylinder of the engine and having a water jacket surrounding the same, and means for varying the volume of said firing chamber. 25

30 In testimony whereof I have signed my name to this specification.

RALPH A. GAERTNER.
